UNITED STATES PATENT OFFICE.

LUEDER RASCHEN, OF ALAMEDA, CALIFORNIA.

TYPE-WRITING MACHINE.

1,070,732.

Specification of Letters Patent. Patented Aug. 19, 1913.

Application filed May 23, 1912. Serial No. 699,167.

To all whom it may concern:

Be it known that I, LUEDER RASCHEN, a citizen of the United States, residing at Alameda, in the county of Alameda and 5 State of California, have invented new and useful Improvements in Type-Writing Machines, of which the following is a specification.

The object of the present invention is to 10 provide a typewriting machine which will permit of the operator writing continuously from one line to the next without having to impart to the carriage any motion other than that accompanying the ordinary printing with the type, thereby reducing the cost of manufacture, increasing the speed attainable on the machine, and materially reducing the noise.

In the accompanying drawings, Figure 1 0 is a plan view of the machine, certain well known parts being omitted; Fig. 2 is a rear view thereof; Fig. 3 is a transverse section.

Referring to the drawing, 1 indicates the bottom or frame of the machine, to which 25 are adjustably secured, as shown at 2, channel-shaped supports 3 for shafts 4 of front wheels 6, and similar supports 7 for the shafts 8 of rear wheels 9. The wheels 6, as also the wheels 9, are suitably spaced 30 from each other to permit of conveniently supporting thereon a cylindrical paper carrier 10.

11 indicates key levers, of a well known type, and drawn upwardly by springs 5, to 35 which levers are hooked, the lower ends of links 13, the upper ends of which are hooked to type-bars 14 carrying type 15 and pivoted upon standards 16 on a circular support 17, so that the type 15 of all of said type-bars, 40 when actuated by the key levers, descend at the same point on the upper surface of the paper carrier 10, being guided in their descent by the vertical guides 18, erected upon a plate 19 secured upon an arch 21 45 supported upon the frame of the machine.

The inking ribbon 22 is in the form of a circular disk, and is secured to a disk 23, a central shaft 24 of which is rotatably supported in said arch. To said shaft is secured a pulley 26, around which travels a band 27 traveling also around a pulley 28 upon a vertical shaft 29 carrying a worm wheel 31 which meshes with a worm 32 on the shaft 4 of one of the wheels 6. Upon 50 the same shaft 4 is mounted a gear wheel 42 controlled by dogs 33 and adapted to be

intermittently rotated by a pawl 34 secured to a spring plate 36, depressed, each time a key lever is actuated, by a universal bar 37 extending longitudinally of the machine 60 and pivoted at its ends, as shown at 39, and adapted to be depressed by any one of the key levers 11. A spring 43 maintains said pawl in engagement with said gear wheel.

By this construction, with each depression 65 of a key lever 11, the gear wheel 32 is rotated through a small arc, thus correspondingly rotating the wheel 6 on the same shaft and correspondingly rotating the cylindrical carrier so as to present a fresh surface 70 of the paper for an impression by one of the type 15. The paper, shown at 41, is folded around the cylinder in a helical form. If it is desired that there should be a blank margin on the right hand side of the paper, said right hand marginal portion is folded under the main body of the paper, when placing the paper around the cylinder. It is retained on the cylinder by any 75 desired means, a simple contrivance for this 80 purpose being rubber bands, shown at 44, around the cylinder and paper, one around the upper portion thereof and the other around the lower portion.

Two supports 7 for the rear wheels 9 are 85 arranged parallel with each other but at any desired obliquity to the frame of the typewriter, and, by reason of this obliquity and the corresponding obliquity at which the wheels 9 engage the cylinder, said cylinder 90 will be caused to have a longitudinal as well as a rotary motion. The degree of obliquity at which the supports 7 and wheels 9 are set will determine the extent of said longitudinal movement with each revolution of the cylinder and therefore also the line spacing. The pitch of the helix in 95 which the paper is wound around the cylinder should correspond with the line spacing, so that, when the paper is unwound, 100 the lines will be parallel with the top and bottom of the paper. By the intermittent rotation of the shaft 4 which carries the gear wheel 32 there will be also produced an intermittent rotation of the vertical shaft 105 29 and therefore also of the circular ribbon 22, so that fresh inking surface is continually supplied.

It is evident that, by this construction, the cost of manufacture and the noise, during operation of the machine are greatly reduced, that produced in the ordinary ma-

chine by the return of the carriage to its initial position being entirely eliminated. On account of this return being no longer necessary the machine can be operated at 5 much higher speed than prior forms of typewriting machines.

I claim:

1. In combination with type bars, a cylindrical paper carrier, means for supporting the same contacting with said paper carrier at its cylindrical surface, means for operating said type-bars, and means for imparting a helical motion to said paper carrier with each such operation.
- 15 2. In a typewriting machine, the combination of a cylindrical paper carrier, wheels

upon which said carrier is rotatably supported, type bars, means for operating said type-bars, and means operated with each operation of the type bars for rotating one of 20 said wheels to rotate the carrier, two such wheels on opposite sides of the carrier being arranged obliquely to the axis of the carrier whereby longitudinal movement is imparted thereto.

25

In testimony whereof I have hereunto set my hand in the presence of two subscribing witnesses.

LUEDER RASCHEN.
